Primary Examiner — John Windmuller*Assistant Examiner* — Luqman McNeil(74) *Attorney, Agent, or Firm* — Husch Blackwell LLP(57) **CLAIM**

The ornamental design for a remote control unit, as shown and described.

DESCRIPTION

FIG. 1 is a front view of a remote control unit showing the new design;

FIG. 2 is a rear view thereof;

FIG. 3 is a bottom view thereof;

FIG. 4 is a top view thereof;

FIG. 5 is a left side view thereof, the right side view being a mirror image of the left side view; and,

FIG. 6 is a perspective view of the front, left side and the bottom thereof.

The broken lines in the figures illustrate unclaimed portions of the remote control unit and form no part of the claimed design.

1 Claim, 5 Drawing Sheets(56)
